US00D498637S

(12) **United States Design Patent** (10) Patent No.: **US D498,637 S**
Heilstedt et al. (45) Date of Patent: **** Nov. 23, 2004**

(54) **FLUID DISPENSING MACHINE**

(75) Inventors: **John E. Heilstedt**, Valparaiso, IN (US);
Steven J. Sorensen, Deerfield, IL (US);
Jon W. Hauser, II, Geneva, IL (US)

(73) Assignee: **Elkay Manufacturing Company**, Oak Brook, IL (US)

(**) Term: **14 Years**

(21) Appl. No.: **29/187,713**

(22) Filed: **Aug. 6, 2003**

(51) LOC (7) Cl. **07-01**

(52) U.S. Cl. **D7/306**; D7/311

(58) Field of Search D7/300, 306, 307, D7/308, 311, 309, 392, 310, 312, 322, 321; 222/129.1, 146.6, 472, 482; 210/748, 192, 85, 232; 99/280, 279, 304, 295

(57) **CLAIM**

The ornamental design for a fluid dispensing machine, as shown and described.

DESCRIPTION

FIG. 1 is a perspective view taken from the top, front and right side of a fluid dispensing machine showing our new design;

FIG. 2 is a top plan view of the fluid dispensing machine shown in FIG. 1;

FIG. 3 is a front view of the fluid dispensing machine shown in FIG. 1;

FIG. 4 is a rear view of the fluid dispensing machine shown in FIG. 1;

FIG. 5 is a bottom view of the fluid dispensing machine shown in FIG. 1;

FIG. 6 is a left side view of the fluid dispensing machine shown in FIG. 1; and,

FIG. 7 is a right side view of the fluid dispensing machine shown in FIG. 1.

1 Claim, 4 Drawing Sheets
